CARRYING CASE FOR SKI EQUIPMENT

Leo Vernon Schaefer, Dayton, Ohio, assignor to Glawe
Manufacturing Company, Dayton, Ohio, a corporation
of Ohio

Filed Feb. 6, 1962, Ser. No. 68,674

Term of patent 14 years

(Cl. D87—5)

FIG.-1

FIG.-2

FIG.-3

FIG.-4

FIG.-5

FIG.-6

FIG.-7

FIG.-8

FIGURE 1 is a perspective view of a carrying case for ski equipment embodying my design and looking in toward one end of the carrying case for ski equipment;

FIGURE 2 is another perspective view of the carrying case for ski equipment but looking in from the other end thereof;

FIGURE 3 is a side view thereof looking in from the right side of FIGURE 1;

FIGURE 4 is another side view thereof looking in from the right side of FIGURE 2;

FIGURE 5 is a plan view thereof;

FIGURE 6 is a bottom view looking up from beneath the carrying case;

FIGURE 7 is an end view looking from the left end of FIGURE 4; and

FIGURE 8 is an end view looking from the right end of FIGURE 4.

I claim:

The ornamental design for a carrying case for ski equipment, substantially as shown.
